PACKAGING OF TABLETS

Charles S. Beardsley, Elkhart, Ind.

Application January 21, 1941, Serial No. 375,149

1 Claim. (Cl. 206—42)

My invention relates, generally, to the packaging of merchandise for sale, and it has particular relation to the packaging of tablets, such as vitamin containing tablets and the like, so that they can be dispensed in limited quantities for individual use.

An object of my invention is to reduce the noise caused by rattling of the tablets after a few of them have been used.

Another object of my invention is to hold the tablets in place in a container and, at the same time, permit a visual inspection of the number remaining.

A further object of my invention is to provide for removing the tablets only one at a time at the will of the user while the remaining tablets are prevented from escaping.

Still another object of my invention is to space the tablets in their container so that they are ordinarily out of contact engagement with each other.

Other objects of my invention will, in part, be apparent and in part appear hereinafter.

For a more complete understanding of the nature and scope of my invention, reference can be had to the following detailed description, taken in connection with the accompanying drawing in which:

Figure 1 is a perspective view of a preferred embodiment of my invention, showing how the tablets may be ejected, one by one, on application of suitable pressure by the thumb of the user;

Figure 2 is a top plan view of the envelope, shown in Figure 1 inside of the rigid box, as it appears before it is inserted in the box;

Figure 3 is a detail sectional view taken along the line 3—3 of Figure 2;

Figure 4 is a view, similar to that shown in Figure 3, and illustrates a somewhat different form of envelope;

Figure 5 is a top plan view of another form of envelope in which the upper wall is formed by transparent material and the lower wall is provided with means for spacing the tablets apart; and

Figure 6 is a detail sectional view, taken along the line 6—6 of Figure 5, showing a portion of the envelope in section and another portion in elevation.

Referring now particularly to Figure 1 of the drawing, it will be observed that the reference character 10 designates, generally, a conventional form of box which is usually formed of metal and comprises a lower portion 11 having

a rigid bottom and rigid side walls, and a cover or lid 12 having a rigid top and rigid side walls. The cover 12 may be hinged, as indicated at 13, to the lower portion 11, or it may be separable therefrom, as will be readily understood.

It is now common practice to dispense tablets, such as vitamin containing tablets, aspirin tablets, etc., in small metal boxes for individual use. The tablets are placed loosely in the box and, as is often the case, when the cover is opened in order to obtain one or two of the tablets, the entire contents, or a considerable portion thereof, may be spilled resulting from the sudden opening of the box. If this is not to occur, then considerable care must be exercised in opening the box so as to prevent loss of any of its contents.

With a view to overcoming this difficulty, I have provided an envelope, shown generally at 14, which is self-contained and which conforms to the shape of the box 10, in this case the box 10 is rectangular as illustrated, and which contains the tablets 15 that would otherwise be loosely disposed in the lower portion 11 of the box 10. By providing the envelope 14, there is little likelihood that any of the tablets 15 will be spilled out even when the box 10 is suddenly opened, and possibly even dropped after being opened.

As shown more clearly in Figures 2 and 3 of the drawing, the envelope 14 has an upper side wall 16 and a lower side wall 17, which initially may be formed by two separate pieces that are suitably secured together along their edges or formed by a single piece suitably folded and secured to form the envelope.

After some of the tablets 15 have been removed, there is a tendency for those which remain to rattle when the box 10 is moved. In order to reduce this noise, one or both of the side walls 16 and 17 can be formed of relatively soft material, such as paper, which serves to deaden the sound and, by conforming generally to the space occupied by the remaining tablets, it serves to hold them in somewhat confined relation.

It is desirable to provide for ready inspection of the contents of the envelope 14 so that the user can determine at a glance the number of tablets which remain. For this purpose a portion 18 of the upper side wall 16 is formed of transparent material, such as wax paper, so that the lower portion, at least, of the envelope 14 can be inspected readily. If desired, the entire upper side wall 16 could be formed of transparent material.

Ordinarily, the user desires to remove from the box 10 only one of the tablets 15. With this in mind I have provided means which permits the tablets 15 to be removed from the envelope 14 only one at a time. As shown in Figures 1 and 2 of the drawings, one corner of the envelope 14 is cut away so as to provide an aperture which is slightly larger than that required to permit movement of the tablets, one at a time, into or out of the envelope 14. As shown, the envelope 14 can be cut along the line indicated at 19 to provide the necessary opening. Then, by the application of a slight pressure just back of the line 19, for instance by the user applying by his thumb 20 a downward pressure on the upper side wall 16, the tablets 15 can be ejected through the aperture only one at a time. Instead of using his thumb, the user can apply the pressure by any other suitable means such as by using a nail file, a pencil, etc.

The capacity of the envelope 14 for holding the tablets 15 can be increased by using the construction shown in Figure 4 of the drawing. As there illustrated, the upper and lower side walls 16' and 17' are joined about their edges so as to provide the rectangular construction indicated at 21.

In Figures 5 and 6 of the drawing, there is illustrated, generally, at 22 another form of envelope that can be used for holding the tablets 15, and which can be used in the box 10 in lieu of the envelope 14, previously described. The envelope 22 comprises an upper side wall 23 and a lower side wall 24. In this embodiment, the upper side wall 23 is formed entirely of transparent material so that all of the tablets 15 within the envelope 22 are visible. The upper side wall 23 can be formed of wax paper, as previously described.

The lower side wall 24 is preferably formed 40

of somewhat more rigid material, such as cardboard, which can be deformed to provide the projections or protuberances 25 extending upwardly therefrom. The projections 25 are so spaced in accordance with the diameter of the tablets 15 that the tablets are held in the spaced relation generally as shown in Figure 5 of the drawing.

The tablets 15 can be readily removed from 10 the envelope 22 in the manner described hereinbefore for the removal of the tablets from the envelope 14. After the first tablet has been removed through the aperture 26 at one corner, 15 additional tablets can be placed in position to be ejected by slightly shaking the box with the aperture 26 in the lowermost position.

Since certain further changes can be made in the foregoing constructions, and different embodiments of the invention can be made without departing from the scope thereof, it is intended 20 that all matter shown in the accompanying drawing and described hereinbefore shall be interpreted as illustrative and not in a limiting sense.

I claim as my invention:

25 A package comprising, a rigid shallow rectangular open top box, an envelope within said box conforming generally to its shape and size and having the upper side wall formed of relatively flexible material, and a single layer of tablets 30 in said envelope, said envelope being closed on all sides and having one corner cut away sufficiently to dispense one tablet at a time by holding the box in the hand and using the thumb to depress the flexible upper side wall portion 35 adjacent said one corner toward the bottom of said box to eject one tablet while at the same time preventing escape of any of the tablets remaining in said envelope.

CHARLES S. BEARDSLEY.
